UNITED STATES PATENT OFFICE.

JOSEPH BUSER MOYER, OF NEW BRITAIN, CONNECTICUT.

STRIP-COILING MACHINE

Application filed July 23, 1921. Serial No. 487,158.

To all whom it may concern:

Be it known that I, JOSEPH BUSER MOYER, a citizen of the United States, residing at New Britain, in the county of Hartford and 5 State of Connecticut, have invented certain new and useful Improvements in Strip-Coiling Machines, of which the following is a specification.

My invention relates to improvements in 10 strip coiling machines for use in rolling mills for coiling sheet steel in strip form, and the object of my improvement is to produce a machine for coiling such strip material that is constructed and arranged so 15 that the coiling will be effected in a manner so as to maintain the side edges of the strip on each side in a common plane and the product will be straight, and thereby avoid unevenness and irregularity as regards 20 the longitudinal direction of the stock:—i. e., whereby the product will be straight instead of crooked.

In the accompanying drawing:—

Figure 1 is a side elevation of my improved strip coiling machine.

Figure 2 is a plan view of the same.

Figure 3 is a fragmentary sectional view on the line 3—3 of Fig. 1.

Figure 4 is a fragmentary sectional view 30 on the line 4—4 of Fig. 1.

Figure 5 is a fragmentary sectional view on the line 5—5 of Fig. 1.

Figure 6 is a sectional view of the general structure on the line 6—6 of Fig. 2.

Figure 7 is a plan view of the bottom strip guiding and supporting plate and adjacent parts, with certain parts broken away.

My improved strip coiling machine comprises a frame that is composed substantially 40 of four uprights or standards 10 in the form of I-beams that are tied together at different elevations by certain cross-pieces that support parts of the mechanism and by crossed 45 or spider-like structures that also support parts of the mechanism, the uprights 10 being at the corners of the frame structure.

The strip is coiled between two plates comprising the bottom plate 11 and the upper 50 plate 12 and is engaged for effecting the coiling by means of a plurality of fingers 13 that project downwardly through the upper plate 12.

The means of support for the bottom plate 55 11 provided by the frame comprise a skeleton, spider-like base 14 that is built up of

I-beams, held together at the junction by means of angle pieces 15 that engage with the web portions of said I-beams. Secured to the skeleton base 14 by screws 16 is the 60 base proper 17 in the form of a circular plate or disc.

A bearing housing structure 18 is secured to the base proper 17 by means of screws 19 that pass through suitable holes in the flange 65 portion 20.

The base proper 17 has a central opening 21 for receiving the reduced bottom end portion 22 of the bottom shaft 23 and resting on the border portion of said opening 21 is 70 a ball bearing device 24 that serves as a thrust bearing for supporting the said bottom shaft 23. The reduced bottom end portion 22 mentioned extends through the opening in the ball bearing device 24 and the 75 bottom shaft 23 is supported from the said ball bearing device through the medium of the shoulder 25 at the junction of the body portion 26 of said shaft 23 and the reduced end portion 22.

The bearing housing structure 18 serves as a housing for the ball bearing device 24 and the body portion 26, being in the form of a sleeve-like structure having a bore that fits said body portion 26 generally and that 85 has an enlarged, chamber portion 27 at the lower end for housing the ball bearing device 24.

For cooperating with the body portion 26 as a guide and side bearing I provide at the 90 upper end portion of the bearing housing structure 18 a bearing bushing 28 of brass or other suitable material.

The upper face of the bearing bushing 28 is opposed to the bottom end face of the hub 95 structure 29 of the bottom plate 11, as shown at 30.

The bottom plate 11 is supported on the upper, reduced end portion 31 of the bottom shaft 23 by means of a shoulder 32 and 100 is held in non-rotative relation thereto by means of a key 33.

The bottom plate 11, as described, is mounted to rotate freely on a vertical axis. The upper face thereof, as shown at 34, is 105 faced off horizontally for engaging with the bottom edge of the strip to be coiled. The plate extends laterally beyond the fingers 13 to the extent desired corresponding to the size of the coil and the lateral 110 edges 35 are beveled to facilitate the admission of the end of the strip to the interior

coiling space and to avoid damaging the edges of the strip.

The top plate 12 is supported by the lower end portion 36 of the upper shaft 37, a key 38 serving primarily to operatively connect the parts for rotative movement and a screw 39 serving to hold the parts in engagement.

The fingers 13, being twelve in number as shown, extend downwardly through holes 40 in the top plate 12, being slidably engaged with the walls of said holes 40.

The said pins 13 have the body portions extended downwardly substantially across the open space 41 between the bottom plate 11 and the top plate 12 and have their upper ends 42 secured in any proper manner in a pin carrier 43 of annular form that loosely overlays the top plate 12 and is mounted for sliding movement along the top shaft 37, and that, furthermore, is adapted to be raised and lowered by means of the lower pin operating lever 44.

An upper shaft operating lever 45, positioned above the lower lever 44, serves as means for raising the top plate 12 and by continued upward movement serves to carry with it the pin carrier 43 and the pins 13, being mounted on and operatively connected with the top shaft 37 in any proper manner for effecting these results.

The structure involved comprises a spider-like device that has sliding engagement with the frame and also may serve to provide an auxiliary bearing for the shaft.

A fixed bearing 46 is provided for the top shaft 37 above the top lever 45 that is supported from the corner posts or standards 10 by means of a fixed spider 47.

Adjacent the upper end of the top shaft 37 is a bevel gear 48 that is held in non-rotative relation thereto by means of a spline 49 which permits the shaft to be raised and lowered relatively thereto for the purpose of changing the open, coil receiving space 41 between the guide plates 11 and 12.

A nut 50 resting on the hub portion 51 of the gear 48 serves as the actual support for the top shaft 37, being engaged with the screw threaded top end portion 52 thereof, a locking screw 53 or any other proper device serving to hold said nut 50 in the position desired for a particular adjustment.

A motor 54 serves as the driving means through the medium of a second bevel gear 55 that cooperates with the gear 48. A brake wheel 56 mounted on the motor shaft 57 may be provided as a convenience for stopping the motor.

Considering the upper lever 45 this extends through the frame in the form of a single and generally straight piece, having the handle 58 at the front, under the motor 54; has a counterweight 59 on the rear arm 60; has the fulcrum in the form of the pin bearing 61 that is supported by the cross-

piece 62 extending across between the rear posts 10; and has a semi-circular part 63 that extends around one side of the adjacent and opposed shaft engaging devices.

A semi-circular cap structure 64 extends around the other side of said shaft engaging devices and is held to the lever 45 by the screws 65.

The means for operatively connecting the shaft engaging devices and the lever 45 comprise a pair of laterally projecting pins or studs 66 on said shaft engaging devices that are entered in suitable slots 67 in the side walls of the enclosing structure composed of the two semi-circular parts 63 and 64, an arrangement that is common in clutch operating mechanism.

The studs 66 are supported by a ring 68, which, as shown, is composed of two mating parts that are held together by means of screws 69. The ring 68 is housed in a recess 70 in the periphery of the sleeve-like bearing housing 73 to be described, being positioned between shoulders 71 at the ends of said recess. Thus the lever 45 is connected to the sleeve-like housing 73.

The said sleeve-like bearing housing 73 has a bore that is composed of a central chamber 74 that terminates at the upper and lower ends in the form of reduced parts 75 of smaller diameter, thus providing shoulders 76 at the junctions. Shouldered sleeve bearings 77 fill the two end portions of the chamber 74, exterior to the shaft 37, and extend outwardly through the reduced parts 75 and serve as bearings for said shaft 37.

In the middle part of the chamber 74 is housed a bearing device 78 that is composed of two similar, mating parts and that cooperates with the opposed portion 79 of the shaft 37 as a thrust or lifting device, the said portion 79 being reduced so as to provide shoulders 80 for cooperating with said bearing device 78.

In the case of the lower lever 44, this has the handle 81 at the front end and the part that passes around the interior, shaft enclosing devices is composed of two arms 82 that are extended rearwardly through the frame structure in the form of a fork, a pivotal connection 92 being provided for each of said arms 82, and a counterpoise weight 84 being mounted on each of said arms 82. The purpose of such forked, duplex construction is to straddle the upper lever 45 and the weight 59 carried thereby, and thus avoid obstruction of one by the other.

The arms 82 have slots 85 for cooperating with laterally projecting studs 86 that are carried by a hub 87. Said hub 87 is part of a spider structure 88 that is provided with a set of four arms, the outer ends of which have sliding engagement with guide-

ways 93 that are provided in shoe structures 94 that are secured to the corner posts 10 by means of the screws 95.

As mentioned, the pin carrier 43 has sliding movement along the shaft 37, and this part is driven by the shaft through the medium of the pins 13, and to this end the said carrier 43 is provided with an inside and an outside bearing. Above the pin carrier proper 43 is a sleeve or neck 83 that has a cylindrical portion 84 that serves as the outside bearing and the structure as a whole has a bore 85 that fits the shaft 37 and serves as the inside bearing.

Referring to the bevel gear 48, this is positioned at a fixed elevation above the bearing 46 and as the shaft 37 is raised and lowered relatively thereto the groove 89 for the spline 49 is raised and lowered accordingly and I prefer to positively avoid having the part of the shaft 37 that has the said groove 89 being received within the active part of the said bearing 46 throughout the range of adjustment that is provided. This result I attain by means of a sleeve 90 that is mounted on the shaft 37 and is seated upon the upper end of the structure of the bearing 46, as shown, the said sleeve 90 thus serving as a spacing sleeve.

A bearing bushing 91 may be seated at the upper end of the sleeve 90 for serving as the active bearing for the bevel gear 48, the hub portion 51 of said gear 48 being seated on the upper face thereof.

In use, the pins 13 combine to form a central core for the coil, the inner end of the strip to be coiled being entered radially between adjacent pins and as the pin structure is turned a hold or bite is obtained on the strip, it being understood that some tension is applied to the strip as may be needed.

The end plates 11 and 12 have flat and parallel face portions that extend outwardly beyond said central core, formed by the pins 13 mentioned and are spaced to fit against the strip to be coiled and thus serve to confine the strip and maintain parallelism of the side edges thereof. In case the strip is coiled hot and in a condition such that it is liable to be distorted, the effect of the arrangement described is to prevent such distortion and to correct any deviation from such parallelism of the side edges.

The bevel 35 on the edge of the bottom plate 11 serves to reduce the liability of damage to the bottom edge of the strip as it enters the coiling space.

I claim as my invention:—

1. A strip coiling machine comprising a frame, a plate operatively supported in said frame for free rotation, a second plate opposed to said first plate and separated therefrom by a coil receiving space, a shaft connected to said second plate, a pin carrier

superimposed on said second plate, coil engaging pins supported by said carrier, projecting through holes in said second plate and slidably therein, and extending into said space, bearing devices for said shaft, adjusting means engaged with said shaft for determining the normal separation of said plates, hand-operated means engaged with said shaft for moving said second plate away from the normal position so as to increase such separation of the plates and operative to simultaneously move said carrier and pins and other hand-operated means engaged with said carrier for moving said pins outward and away from said space independent of said first-mentioned hand-operated means.

2. In combination in a strip coiling machine, a pair of opposed end plates positioned in spaced relation for engaging with the edges of the strip being coiled, driving means for one of said plates, coil engaging pins projected through the driven plate into the space between the plates, and means for withdrawing said pins from said space.

3. A strip coiling machine comprising a central core structure that is bordered by a pair of end plates in spaced relation, driving means operative directly to drive said core structure and one of said plates, and the other of said plates being mounted for free rotation in a fixed plane independently of the first-mentioned plate.

4. In a machine for coiling metal in strip form, a core for supporting the coil at the axis and a pair of end plates opposed to the edges of the strip, means for adjusting the position of the plates relatively one to the other so as to fit closely to said edges, and for operating upon said strip while heated to a relatively high temperature so that as the strip is delivered to the space between the end plates during the coiling operation distortion of the strip will be substantially prevented.

5. In a strip coiling machine, a pair of end plates having opposed faces substantially flat and plain and separated by a coil receiving space and mounted for rotation, a core structure for the coil in the form of a plurality of pins projected from one of said plates into said space, and means for withdrawing said pins from said space while the plates remain substantially unchanged in their relative positions, whereby the coil can be freely removed in the radial direction from said space after said pins have been withdrawn.

6. In a strip coiling machine, a backing plate supported for free rotation in a fixed radial plane, a driving plate opposed to said backing plate, separated therefrom by a coil receiving space, and provided with a core structure that projects into said space, and hand-operated means for moving said

driving plate toward and away from said backing plate.

7. A machine for use in the production of steel in strip form having means for operating upon the strip during the cooling thereof after delivery from the rolls, said means comprising a pair of plates having plain faces, means for positioning said

plates so that they will be opposed one to the other and separated by a space having a width approximately equal to the width of the strip, and means for maintaining said strip in said space during the cooling thereof and with the lateral edges opposed directly to the opposed faces of said plates.

JOSEPH BUSER MOYER.
